CLAIM

I claim the ornamental design for a modular customization kit for a work vehicle, as shown and described.

DESCRIPTION

FIG. 1 is a perspective view of a rear portion of a work vehicle illustrating my design for a modular customization kit, comprising a front cabinet, a pipe rack with a quantity of pipe therein, and a second cabinet situated above the pipe rack, pursuant to an embodiment of the invention.

FIG. 2 is a perspective view of a rear portion of a work vehicle illustrating my design for a modular customization kit, comprising a front cabinet, wherein the pipe rack and second cabinet are both omitted for improved illustration of the front cabinet only, pursuant to an embodiment of the invention.

FIG. 3 is a cutaway top view of a rear portion of a work vehicle illustrating my design for a modular customization kit, pursuant to an embodiment of the invention.

FIG. 4 is a cutaway side view of a rear portion of a work vehicle illustrating my design for a modular customization kit, pursuant to an embodiment of the invention.

FIG. 5 comprises a front view of a front cabinet, pursuant to an embodiment of the invention.

FIG. 6 comprises a side view of a front cabinet, pursuant to an embodiment of the invention.

FIG. 7 comprises a top view of a front cabinet, pursuant to an embodiment of the invention.

FIG. 8 comprises a front view of a pipe rack and second cabinet, pursuant to an embodiment of the invention.

FIG. 9 comprises a side view of a pipe rack and second cabinet, pursuant to an embodiment of the invention; and, FIG. 10 comprises a top view of a pipe rack and second cabinet, pursuant to an embodiment of the invention.

The broken lines illustrating a work vehicle depict environmental matter and form no part of the claimed design.

1 Claim, 6 Drawing Sheets
